United States Patent Office.

EPHRAIM VORBE, OF SAN FRANCISCO, CALIFORNIA.

Letters Patent No. 89,817, dated May 4, 1869.

IMPROVEMENT IN COMBINATION-LOCKS.

The Schedule referred to in these Letters Patent and making part of the same.

To all whom it may concern:

Be it known that I, EPHRAIM VORBE, of the city and county of San Francisco, State of California, have invented an Improved Combination-Lock; and I do hereby declare the following description and accompanying drawings are sufficient to enable any person skilled in the art or science to which it most nearly appertains, to make and use my said invention or improvements, without further invention or experiment.

My invention relates to that class of locks known as combination, and used principally for safes and vaults; and

It consists, first, of an improved manner of setting the tumblers and operating the bolt; and, secondly, a stop for the bolt, which is operated by a lever and a series of toothed wheels, which are in turn operated by an arm on the tumbler-shaft.

These toothed wheels are set before locking the safe, so that if the combination is not made correctly at the first trial, the stop will be forced out, and prevent the bolt being moved.

By means of the wheels and the lever, before mentioned, the stop will be forced back into its place, when a second trial can be made, and the bolt can be drawn if the combination is correct; but if a second mistake be made, the stop cannot be again forced back till the last toothed wheel has been turned half around, which would necessitate an immense number of turns of the knob.

The bolt is operated by an independent knob, having an opening, into which a key of peculiar construction must be introduced. This key presses back a number of small arms, by means of spindles, so that they will move in grooves in a circular arc, and thus allow the knob to be turned, and the bolt moved.

The combination may be changed at any time, by means of a series of smaller disks within the tumblers, and concentric with them, and which are secured by set-screws.

To more fully describe my invention, reference is made to the accompanying drawings, forming part of this specification, of which—

Figure 1, sheet 1, is an outside view of the knobs. Figure 2 is a sectional view, taken through *xx*, fig. 1. Figure 3, sheet 1, is a sectional view, taken through *yy*, fig. 1.

Figure 4 is a view of the bolt and the operating-mechanism.

Figure 5, sheet 2, is a view of the operating-wheels of the bolt-retainer.

Figure 6 is a back view of the lock.

Similar letters of reference in each of the drawings indicate like parts.

A represents a section of the door-plate of the safe, or the supporting-plate of the lock, and to which the lock is fastened.

Two openings are made through this plate, one for the spindle *C*, which operates the tumblers, and the other for the one *D*, which moves the bolt.

A secondary plate, *B*, is fastened to the inner face of the door-plate *A*, and has oblong openings through it, which correspond with the openings for each of the knobs, and are made larger at one end than at the other, so that the short spindles *C* and *D* may be introduced from the outside, and passed through both the plates *A* and *B*; after which the plate *B* is moved, so that the smaller portion of the openings encircle the necks or grooves in these spindles at the points *a a*, thus preventing their being withdrawn.

Each of the spindles *C* and *D* has a square opening made in its outer end, of sufficient depth to admit the square ends *b b'* of the stems *c c'*.

These stems hold the knobs *E* and *F* in their places, by means of the disks or plates *K K'*, which set down over collars on the lower ends of the stems.

The square openings serve to turn the spindles, and move the interior mechanism of the lock, when the knobs are operated, but are so shallow that, should the knobs be moved, there would be no opening or communication with the interior of the lock.

The knob *E* is fastened to the stem *C* by a screw, *G*, or other suitable device, and has on one side a sliding bolt, *d*, which may be moved out or in, so as to engage the projection on the outer disk, or not, as desired.

There are three of these disks, *H*, *I*, and *J*, forming a low cone, the inner one, or that which is nearest the door-plate, being the largest, and resting on the disk *E*, which is fastened to the plate *A*.

The conical disks *H*, *I*, and *J* carry small projections or lugs, *e*, *f*, and *g*, which are operated by the bolt *d*, and by each other.

The disk *K* has a sleeve, *L*, arising from its centre, and through which the stem *c* passes.

This sleeve has one side flattened slightly, and the washers *h*, *i*, and *j*, between the disks, are so made as to fit this sleeve, as shown at *L*, and thus remain stationary, while the disks turn freely between them.

The knob *F*', by which the bolt is operated, is fastened to the stem *c* by a set-screw, *F*, and has an opening in the centre, at the top, sufficiently large to admit the key *M*, and extending down to near the top of the stem *c*', at which point it is contracted, so as to just allow the slender stem *k* to pass through.

A small lug projects into the key-hole, as shown at *l*, and the side of the key is slotted in a peculiar manner, so as to allow it to pass in, and be turned partially around.

Within the lock are the tumblers *N*, *O*, and *P*, which are operated from the spindle *C*, the toothed wheels *Q*, *R*, *S*, and *T*, the bolt *U*, and the device contained in the case *V*, and connected with the knob *F* and the key, so as to operate and control the movements of the bolt.

These tumblers *N*, *O*, and *P* are circular disks, with a slot on one side, and having within them, and concentric with them, the smaller disks, as shown at *N'*, fig. 5.

These smaller disks are movable within the tum-

blers, by loosening the set-screws m , so that a new combination may be made, when they are again made tight.

Within the disks N' are small sleeves, O' , around which the tumblers and the combination-disks revolve, but which are themselves stationary, as they fit the central stem, which is square where it passes through them. Each of the disks N' has a small piece of metal, n , passing through it, or fastened to it, and forming a lug on each side, so that the lug n' , on the inner end of the spindle C , operates the first tumbler N by means of its lug, turning it till it comes in contact with the lug of the next tumbler, O , when that is likewise moved, and the last, in the same manner.

The lug of the tumbler P operates the arm p , and this in turn moves the ratchet Q , by means of the vibrating arm W , carrying the pawl X .

The pawl Y is stationary, and holds the ratchet when the pawl X is moved back one tooth, by turning the knob E (and by its agency eventually the tumblers and the arm p) in an opposite direction.

The toothed wheel R is moved forward one tooth by a whole turn of the ratchet Q , by means of a larger tooth on one side; the wheel S , in the same manner, by R , and T by S . The wheel T has two pins on its outer side, by which the lever Z is moved, and the stop R forced back into place.

The bolt U is made with a slot transversely, within which the stop R moves, being thrown out, when released, by the spring T' .

The stop has a small spring, r , which, when it is pressed back, forces the sliding-plate r' down, so that the slot through which the rear end, R^2 , of the stop passes, holds it, by means of a small shoulder.

The sliding-plate r' releases the stop when it is pressed back by contact with the tumblers, which happens when the combination is not set right. When an attempt is made to draw the bolt, when the stop is out, the stop is brought into contact with a post, s , which prevents any further motion till, by means of the lever Z , the stop has been returned to its place.

A flat plate, s' , extends back from the bolt, and is connected with the oblong hollow case or chamber V by means of a link, t . The chamber is made with a square opening at the lower or front end, so as to fit over the end of the spindle D , and be turned by it, thus moving the bolt.

Within the chamber is a sliding block or plate, u , having the arms 1, 2, and 3 projecting through one side of the chamber, and a little beyond it.

A spring, V' , keeps the plate u down against the front face of the chamber until the key is inserted in the knob, as before described.

A small stem, k' , is fastened to the plate u , and extends nearly through the spindle D , in a line with the stem k , so that as k is pressed down by the key, it moves K , and forces the plate u back, carrying with it the arms 1, 2, and 3.

Around the outside of the case V is placed a plate, w , carved so as to form a segment, having the same centre as the case.

This segment is firmly fastened to the lock-plate, and is grooved, as shown at w' , fig. 3, so that when the arms 1, 2, and 3 are raised, they will move in these grooves, but when the key is removed, the arms would be stopped by the edge of the plate w , and the bolt

could not be moved, even if the combination were correctly set.

The operation of my lock is as follows:

Before locking the safe, the small knobs 4, 5, 6, and 7, on the back of the lock, and which are attached to the spindles of the toothed wheels Q , R , S , and T , respectively, are turned around till their indices point to the dots shown on the lock-plate outside their periphery. This brings the wheels into a position where each is ready to act on the next, if moved, and also moves the lever Z , and presses the stop R' back, so that the bolt can move.

To unlock the safe, the knob E is turned till the bolt or pin d is brought into contact with the lug e , e with f , and f with g . The combination being known as 10, 20, and 40, or any other desired, the disks H , I , and J are all turned till the proper number on the disk J corresponds with the point or index G' on the plate K . The knob is then turned back and forward till the numbers on the disks I and H successively are brought into line. The key M is then inserted in the key-hole in the knob F , and turned to a position where it will hold the arms 1, 2, and 3, before described, opposite the grooves w , w' , in the segment w .

The setting of the numbers correctly brings the slots n' in the tumblers into a line with the sliding plate r' , so that as the knob F is turned, and the bolt withdrawn, the plate r' enters the line of slots in the tumblers, and the safe is unlocked.

But if the combination be incorrectly made, the slots n' will not all be in the proper line, and when the attempt is made to draw the bolt, the plate r' strikes the edge of some one of the tumblers, and releases the stop R' , which flies out, and makes it impossible to move the bolt. It will then be necessary to turn the knob E and the tumblers till the lug n , on the tumbler P , shall move the arm p , thus turning the arm W , pawl X , and the wheels Q , R , S , and T , the last one, T , moving the lever Z , and pressing the stop R' back into place. If the mistake be made a second time, the knob will have to be turned back and forward a very great number of times, till the wheels are again brought to their first position, before another trial can be made.

Having thus described my invention,

What I claim as new, and desire to secure by Letters Patent, is—

1. The combination of the stem c' , holding-plate k' , and socket-stem D , substantially as described.
2. The stop R' , with the catch r , the sliding plate r' , and spring T , for holding and releasing the stop, substantially as and for the purpose herein described.
3. The tumblers N O E , with the lugs n , n' , the arm p , the wheels Q R S T , and the lever Z , the whole operated from the knob E , for retreating the stop R' , substantially as described.
4. The device for controlling and operating the bolt, consisting of the rotating case V , the plate u , with its arms 1, 2, and 3, the spring V' , the stems k , k' , and the key M , together with the slotted segment w , the whole connected and operated substantially as herein described.

In witness whereof, I have set my hand and seal.
